CLAIM

The ornamental design for an industrial vacuum cleaner, as shown and described.

DESCRIPTION

FIG. 1 is a perspective view of a first embodiment of an industrial vacuum cleaner according to the design;

FIG. 2 is a right side view thereof;

FIG. 3 is a left side view thereof;

FIG. 4 is a front view thereof;

FIG. 5 is a rear view thereof;

FIG. 6 is a top view thereof; and

FIG. 7 is a bottom view thereof.

FIG. 8 is a perspective view of a second embodiment of an industrial vacuum cleaner according to the design;

FIG. 9 is a right side view thereof;

FIG. 10 is a left side view thereof;

FIG. 11 is a front view thereof;

FIG. 12 is a rear view thereof;

FIG. 13 is a top view thereof; and,

FIG. 14 is a bottom view thereof.

The broken lines shown in the drawings depict portions of the industrial vacuum cleaner that form no part of the claimed design.
